REFRIGERATION

George C. Pearce, Dayton, Ohio, assignor, by
mesne assignments, to General Motors Cor-
poration, a corporation of Delaware

Application September 29, 1932, Serial No. 635,390
Renewed May 2, 1936

16 Claims.

(Cl. 62—4)

This invention relates to refrigeration, and more particularly to refrigerating systems of the character which operate continuously without stopping for temperature adjustments in an object being cooled. Such systems are stopped a relatively few times compared with the stopping operations of the usual intermittently operating refrigerating system which stops for temperature adjustments in the objects being cooled. In the continuously operating systems or in those systems which are designed to operate substantially continuously with and stop only for defrosting, repairs or the like, or when the atmospheric temperature drops below the normal range, the period of idleness is extremely long, so that the refrigerant pressure in the system will become substantially equalized throughout the system. Because of this, these systems need not, and generally are not, provided with special unloaders for the compressor, and therefore are likely to fail to restart if an attempt is made to restart them relatively soon after they have been stopped. It may occur in the operation of these systems that the line current, or source of electrical energy, may fail for a relatively short period of time, due to an electrical storm or the like, and it is desirable that the refrigerating system should restart automatically and safely after such a temporary failure of the line current. It is among the objects of this invention to provide an improved control for the electric motor which drives the refrigerating system which is capable of automatically starting the motor when the current is turned on by the user and also which is capable of restarting the system safely if the line current, or source of electrical energy should be turned off temporarily and then be turned on before the refrigerant pressure has equalized sufficiently to permit the motor to start. Further objects and advantages of the present invention will be apparent from the following description, reference being had to the accompanying drawing, wherein a preferred form of the present invention is clearly shown.

In the drawing:

The figure is a diagrammatic representation of a system embodying the features of my invention.

A refrigerating system embodying features of this invention is designed to operate continuously without stopping for temperature adjustments and is of such a character and capacity, that it automatically maintains proper temperature conditions in the object to be cooled, notwithstanding such continuous operation. Such a system has been more fully described in the copending appli-

cation, Serial No. 599,239, filed March 16, 1932, to which reference is hereby made for a further disclosure of such a system.

Briefly, such a system includes a compressor 10, a condenser 11, an evaporator 12. The compressor discharges the compressed refrigerant to the condenser 11 which in turn discharges liquefied refrigerant through the expansion device 13 to the evaporator 12 where the refrigerant is evaporated and returns through the line 14 to the compressor 10. The expansion device 13 may be of any suitable character, but preferably is of the elongated orifice type which maintains a fixed, and continuously open orifice, so calibrated as to length and cross-sectional area, that it maintains the evaporator 12 at the proper temperature to maintain the object being cooled at a substantially constant temperature notwithstanding variations in the surrounding atmosphere. In such a system, the elongated orifice in the expander 13 permits a continuous passage of refrigerant therethrough, and should the compressor 10 stop temporarily, this flow through the orifice continues and in a relatively short time equalizes the pressures throughout the refrigerating system, so that if the compressor should be restarted after such a short time, it starts with substantially no load.

Under ordinary conditions, such a system is stopped only for the purpose of defrosting the evaporator 12 and this defrosting operation is performed only once or twice a month and is not of the type of stopping operation which is intended to maintain temperature conditions in the object being cooled. On the contrary, such a stopping operation generally permits the object being cooled to warm above the desired temperature, but the operation is performed because of the large accumulation of frost on the evaporator and because of its undesirable inconvenience. After such a stopping operation and because of its long duration, the compressor starts under no load characteristics and hence the compressor need not be provided with unloading mechanism, other than the expander 13 itself. The motor 15 for driving the compressor may be of the split phase type which is provided with a starting winding 16 and a running winding 17, and, as is usual with this type of motor the starting torque is small. Such a motor compressor unit is capable of starting only if the entire refrigeration system has become substantially equalized as to pressure throughout, or if the unit is provided with an automatic unloader for removing the pressure differential load during the starting period. In

this particular system, no unloader need be used, as it is possible to permit the system to equalize by a sufficiently long period of idleness during the infrequent stops which may be necessary.

5 The control for the motor includes starting contacts 18 for controlling the flow of electric current to the starting winding and running contacts 19 for controlling the flow of electric current to the running windings. A starting control 20 is provided for the contacts 18 and a running control 21 is provided for the contacts 19. The control 20 includes a thermostat in the form of a bi-metallic strip 22 heated by a resistance 23 in an electric circuit between the 10 source of electrical energy 24 and the motor 15 which passes through the resistance 23. The bi-metallic strip 22 opens the contacts 18 by moving the rod 18a carrying the movable contact upwardly against the magnet resistance 25 by a snap action in the well-known manner. The running control 21 includes a thermostat in the form of a bi-metallic strip 26 heated by a resistance 27 through which an electric circuit passes from the source of electrical energy 24 to the motor 15. 15 The strip 26 opens the contacts 19 by moving the rod 19a carrying the movable contact upwardly by a snap action against the magnet resistance 28.

The construction and calibration is such that 20 the thermostat 20 opens the contacts 18 after the motor 15 has attained its running speed and maintains the contacts open so long as the motor continues to operate normally. The control 21 is constructed and calibrated so that the contacts 19 remain closed so long as the motor runs normally but will open if the motor should become overloaded sufficiently to overheat the thermostat 21 and cause it to open the contacts 19. Also the construction is such that the thermostats automatically reclose their respective contacts when they have cooled either because the current has been turned off intentionally or accidentally. To this end the resistances 23 and 27 are placed in the circuit leading to the running winding 17, so that both thermostats 20 and 21 are responsive to the current flowing to the running winding. However, the thermostat 20 is constructed so that it heats quickly and opens the contacts 18 before the contacts 19 can be opened and is of such construction that the contacts 18 are opened after a predetermined period of time sufficient to normally permit the motor 15 to attain its running speed.

A manual control for stopping and starting the system may be provided and this may include a snap acting lever mechanism 30 adapted to engage the hook 31 which is an extension of the contact rod 19a which controls the opening and closing of the contacts 19. The rod 19a may have a sliding engagement with the strip 26 with a stop 33 attached to the rod 19a in such a manner that the rod 19a may be moved upwardly without disturbing bi-metal 26. Thus the manual control 30 may be operated to open the contacts 19 by moving hook 31 and therefore the rod 19a upwardly without disturbing the bi-metal 26, and if the manual control 30 is placed in the closed position, it permits the rod 19a to move downwardly and be actuated by the bi-metal 26 acting through the stop 33 independently of the manual control.

Under ordinary operation, the manual control 30 is moved to release the rod 19a downwardly to close the contacts 19 and this initiates a starting cycle in which electric current flows

through both windings 16 and 17 and both resistances 23 and 27. After a length of time sufficient to permit the motor to start, the contacts 18 are opened by an upward movement of the rod 18a thus opening the circuit 34 leading to the starting winding after which the motor 15 will be operated only by the running winding. Should the source of electrical energy, or line, temporarily fail and be reenergized before the refrigerant pressure in the system has equalized sufficiently to unload the compressor, upon the return of electrical energy the motor 15 probably will fail to start either because the resistance 23 has not had time to cool and close contacts 18 or will fail to start because the pressure differential in the compressor and therefore its starting torque is too great for the motor. In either case, the running thermostat 21 will become overheated and the contacts 19 will be opened. When these contacts are open, the flow of current through the resistances 23 and 27 stops and permits the thermostats 20 and 21 to cool, thus reclosing the contacts 18 and 19. When these contacts are reclosed, a starting cycle is initiated which if successful will permit the motor 15 to run as long as desired, but if unsuccessful, will re-initiate another overload and restarting cycle until such time as compressor is unloaded sufficiently to permit the motor 15 to start.

While the form of embodiment of the invention as herein disclosed, constitutes a preferred form, it is to be understood that other forms might be adopted, all coming within the scope of the claims which follow.

What is claimed is as follows:

1. A refrigerating system comprising a compressor, condenser, a constantly open liquid refrigerant control device and evaporator in a closed refrigerant flow circuit, an electric motor for driving said compressor having a starting torque insufficient to start the compressor against pressure differences of the order existing thereacross during normal operation of the apparatus, said motor having a starting winding and a running winding, starting contacts for controlling an electric circuit through said starting winding, a starting thermostat responsive to current flow through said running winding for opening said contacts, running contacts for controlling an electric circuit through said running winding, a running thermostat responsive to current flow through said running winding for opening said running contacts, said thermostats being adjusted to open said starting contacts only after the motor has attained a speed sufficient normally to insure operation on the running winding, and to open said running contacts only when said motor is overloaded.

2. A refrigerating system comprising a compressor, condenser, a constantly open liquid refrigerant control device and evaporator in a closed refrigerant flow circuit, an electric motor for driving said compressor having a starting torque insufficient to start the compressor against pressure differences of the order existing thereacross during normal operation of the apparatus, said motor having a starting winding and a running winding, starting contacts for controlling an electric circuit through said starting winding, a starting thermostat responsive to current flow through said running winding for opening said contacts, running contacts for controlling an electric circuit through said running winding, a running thermostat responsive to current flow

in the running winding of said motor and controlling the flow of current to said motor, said starting thermostat being adjusted to open said starting contacts only after the motor has attained a speed sufficient normally to insure operation on the running winding, and said overload control being adjusted to prevent the flow of electric current to said motor only when said motor is overloaded, said thermostat and overload control automatically reclosing after a predetermined period.

9. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, thermal current means adapted to open the first circuit controller when the motor approaches running speed after starting, and current responsive means for opening the second circuit controller upon the flow of excessive current and for automatically closing the second circuit controller after an interruption of the flow of current to the running winding.

10. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, thermal current means adapted to open the first circuit controller when the motor approaches running speed after starting, and thermal current responsive means for opening the second circuit controller upon the flow of excessive current and for automatically closing the second circuit controller after an interruption of the flow of current to the running winding.

11. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, thermal current means adapted to open the first circuit controller when the motor approaches running speed after starting, and current responsive means for opening the second circuit controller upon the flow of excessive current and for automatically closing the second circuit controller after an interruption of the flow of current to the running winding, said last named means including time delay means for preventing maintenance of the second circuit controller in closed position until a predetermined

time has elapsed after the occurrence of an excessive current flow in the motor.

12. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, thermal current means adapted to open the first circuit controller when the motor approaches running speed after starting, and thermal current responsive means for opening the second circuit controller upon the flow of excessive current and for automatically closing the second circuit controller after an interruption of the flow of current to the running winding, said last named means including time delay means for preventing maintenance of the second circuit controller in closed position until a predetermined time has elapsed after the occurrence of an excessive current flow in the motor.

13. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling both motor windings, thermal current means adapted to open the first circuit controller when the motor approaches running speed after starting, and current responsive means for opening the second circuit controller upon the flow of excessive current and for automatically closing the second circuit controller after an interruption of the flow of current to the running winding.

14. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling both motor windings, thermal current means adapted to open the first circuit controller when the motor approaches running speed after starting, and thermal current responsive means for opening the second circuit controller upon the flow of excessive current and for automatically closing the second circuit controller after an interruption of the flow of current to the running winding.

15. Refrigerating apparatus including a closed refrigerating system comprising a compressor, a condenser, and an evaporator, an electric motor connected to the compressor for driving the compressor, said electric motor including starting and running windings, said electric motor being supplied with electric energy through an electric circuit, said compressor being driven by said elec-

tric motor for circulating refrigerant in the closed refrigerant system by creating a pressure difference on opposite sides of the compressor, said closed refrigerant system being provided with 5 means for reducing the pressure difference on opposite sides of the compressor when the compressor is idle to unload the compressor, starting contacts in series with the starting winding to control the energization of the starting winding, a starting 10 thermostat for controlling the opening of said contacts, and a self-resetting overload device responsive to the overloading of the electric motor for opening the electric motor circuit for preventing the energization of the electric motor 15 when the pressure difference on opposite sides of the compressor has not been reduced sufficiently to permit starting of the electric motor, said self-resetting overload device being provided with means for re-closing the motor circuit after an 20 interval.

16. Refrigerating apparatus including a sealed casing containing a compressor and an electric motor connected to the compressor for driving the compressor, said electric motor including starting and running windings within the sealed 5 casing, said windings being supplied with electric energy through an electric circuit, a refrigerant condenser and a refrigerant evaporator connected in closed refrigerant circuit with said compressor, said compressor being driven by said electric motor for circulating refrigerant in the system by creating a pressure difference on opposite sides of the compressor, and a single thermostat located outside the sealed casing for controlling 10 both the energization and the de-energization of the starting winding independently of the running winding. 15
